SWITCH AND SIGNAL CONTROL SYSTEM
FOR RAILROADSCharles L. Swanton, North Chili, N. Y., assignor
to General Railway Signal Company, Rochester, N. Y.

Application May 2, 1940, Serial No. 332,971

11 Claims. (Cl. 246—134)

This invention relates to switch and signal control systems for railroads, and it more particularly pertains to the power operation of track switches in a switch and signal control system of the entrance-exit type.

In an entrance-exit switch and signal control system, a control machine at a tower or control office is provided with a control panel upon which is a miniature track diagram corresponding to a track layout in the field for which the system is provided. Disposed on such diagram at points representative of the signal locations are control buttons by the actuation of which an operator can designate the entrance and exit ends of each route he desires to be set up. Responsive to such designation, a route establishing means such, for example, as is disclosed in the prior application of A. Langdon, Ser. No. 119,641, filed January 8, 1937, and in the patent to A. Langdon, Patent No. 2,148,865, dated February 28, 1939, automatically selects the required position for each of the track switches in that route. The direction for which each route is to be established is defined by a particular distinctive manner in which the operator designates the ends of such route by the actuation of the control buttons on the miniature track diagram.

An object of the present invention is to provide in an entrance-exit system cross-protection means for preventing the unauthorized operation of track switches or other devices in the field when an extraneous source of energy is applied to the control wires of such device.

More specifically, for example, the control circuits for operating the track switches to opposite positions from those positions such track switches have last assumed, are maintained closed and de-energized at all times except when such opposite positions of the track switches are called for, each of such circuits including a polar cross protection relay located at the control office. Thus, if a cross occurs between the normal or reverse control wires of two power switches, the application of energy to either of such wires causes the operation of the cross protection relay for the track switch having its control wire improperly energized, if such energy is of the proper polarity to cause such track switch to be operated. The detection of a cross by a cross protection relay under such conditions trips a circuit breaker to immediately deenergize all of the switch control circuits and thus remove energy from the circuit improperly energized. After the cross has been removed, the cross protection relay and

the circuit breaker are respectively manually restored to their normal conditions.

Another object of the present invention is to open the switch control circuit last used for the operation of a track switch at the control office when that track switch has completed its operation, thus rendering the normal and reverse switch control wires both deenergized except when the track switch is out of correspondence with the last position called for. It is further provided when such circuits are deenergized that the normal and reverse switch control wires are both connected through the winding of the cross protection relay for that track switch to a common switch control wire.

Another object of the present invention is to provide in an entrance-exit system dynamic braking for each of the switch machine motors when that switch machine has completed its operation, such dynamic braking being dependent upon the closed circuit principle as used in connection with the cross-protection means employed.

Another object of the present invention is to provide in an entrance-exit system an arrangement of circuits whereby switch operating wires are energized in accordance with the condition of switch control relays at the control office having heavy duty magnetic blow-out contacts, whereby the overloading of the switch machine control circuits is prevented by an overload relay at the control office, whereby a cross-protection relay for each track switch is located at the control office where it can be readily restored, and whereby a circuit breaker is located at the control office for use in connection with the cross-protection means.

Other objects, purposes and characteristic features of the present invention will be in part obvious from the accompanying drawings and in part pointed out as the description of the invention progresses.

In describing the invention in detail reference will be made to the accompanying drawings in which like reference characters designate corresponding parts, in which parts having similar functions are designated by similar letter reference characters having distinctive preceding numerals or preceding letter reference characters indicative of the signal locations with which such parts are associated, and in which:

Figs. 1A and 1B, when placed end-to-end, illustrate one embodiment of the present invention as applied to the power operation of the track switches of a simple track layout in ac-

cordance with the entrance-exit designation of each desired route to be established by the actuation of respective entrance and exit buttons by an operator at the control office.

The various parts and circuits constituting the embodiment of the present invention have been shown in a diagrammatic manner rather than showing the specific construction and arrangement of parts as provided in practice, for the purpose of facilitating the disclosure of the present invention as to the mode of operation and principles involved. Thus, the various relays and their contacts are illustrated in a conventional manner, and symbols are used to indicate the connections to the terminals of batteries or other sources of electric current instead of showing all of the wiring connections to those terminals.

The symbols (+) and (−) are employed to indicate the positive and negative terminals respectively of suitable batteries or other sources of direct current, and the circuits with which those symbols are used always have current flowing in the same direction. If alternating current is used, the symbols (+) and (−) are to be considered as relatively instantaneous polarities.

For convenience in describing the present invention reference is made from time to time to parts of a general nature as characterized by the letter reference characters common to such parts. Such reference is to be considered as applicable to any of the parts designated in the drawings by similar letter reference characters having preceding numerals or letters representative of the various signal locations.

Track layout.—Although the present invention is applicable for use with practically any track layout encountered in practice, for the purpose of simplifying the disclosure of the present invention, the embodiment of the invention as illustrated in Figs. 1A and 1B is applied to the governing of train movements through the track layout illustrated in Fig. 1B. It is to be understood that the system provided for the control of each of the track switches in such track layout is typical of the means by which the system is applied to the control of single track switches and crossovers of any particular complex track layout encountered in practice. The track layout illustrated in Fig. 1B is a type which might be encountered in practice at either end of a station platform, there being a more direct through route, and two other tracks assumed to be coming from different platforms converging by respective track switches into a single track extending away from the station platform.

Signals are provided for governing traffic through the track layout, signals A and B governing east bound traffic to the right through the track switch 2, and signals D and E governing east bound traffic through the track switch 3. West bound traffic to the left through track layout is governed by signal F through track switch 3 and by signal C through track switch 2. For the purpose of simplicity, it is assumed that each of the signals governing traffic through the track layout is of the low speed or dwarf color light type having a red lamp for indicating stop, and a yellow lamp for indicating proceed. It is to be understood that additional indications can be readily provided for track layouts where high speed traffic is permitted, the higher speed indications being distinctive by the illumination of green lamps, for example, in accordance with automatic control dependent upon the condition of occupancy of the trackway in advance of such

signals and dependent upon the indication displayed by the next signal in advance. It is also to be understood that other types of signals such as semaphore and search light signals can as well be used.

Each of the track switches 2 and 3 is power operated by a switch machine SM, the switch machine 2SM being provided for the positioning of track switch 2, and the switch machine 3SM 10 being provided for the positioning of track switch 3. Each of the switch machines SM can be, for example, of the type disclosed in the patent to W. K. Howe, Patent No. 1,466,903, dated September 4, 1923, and in addition to the structure disclosed in that patent such switch machine can also contain a brake as disclosed in the patent to W. K. Howe, Patent No. 1,852,574, dated April 5, 1932, and associated with the switch machine a point detector contact mechanism can be provided as shown, for example, in the patent to C. S. Bushnell, Patent No. 1,517,236, dated November 25, 1924.

A polar neutral relay WP is provided for each of the track switches for repeating its position 25 in correspondence with the switch machine for that track switch in a manner well known to those familiar with the art. Each of such WP relays is energized with one polarity when its track switch and switch machine are locked in a normal position and is energized with the opposite polarity when the track switch and switch machine are locked in a reverse position, such WP relay being deenergized except when either of those two conditions is fulfilled.

30 The track layout is divided into track sections in the usual manner, there being detector track section 2T for the track switch 2, and a detector track section 3T for the track switch 3. It is to be understood that the usual type of track circuits is provided for each of the track sections for the energization of its respective track relay TR in a manner well known to those familiar with the art, and that the track switches are properly bonded to provide fouling protection.

45 *System device.*—With reference to Fig. 1A, a portion of the miniature track diagram of the control panel of the control machine for governing train movements through the track layout illustrated in Fig. 1B is shown, such portion 50 being for traffic through the portion of the track layout conveniently called an "interlocked group" bounded by signals A, B, and C. Inasmuch as such interlocked group corresponds in general character to the adjacent interlocked group bounded by signals D, E and F, for the purpose of simplicity, the portion of the control machine relative to the control of such adjacent interlocked group has not been shown, as it is believed to be readily apparent to those familiar 55 with the art that the means for governing traffic through such interlocked group is practically identical to that illustrated in detail and about to be described for the group bounded by signals A, B and C. Thus, with reference to Fig. 1A, entrance buttons ANB, BNB and CNB are provided on the control panel at points in the miniature track diagram corresponding to the relative location of the signals A, B and C for designation of the entrance points for routes to be established governed by such respective signals. In a similar manner, the exit buttons AXB, BXB and CXB are provided for designation of the exit points for the respective signal locations A, B and C.

75 Each of the entrance buttons NB is of the

self-restoring type, having a contact closed only when the button is depressed and another contact closed when such button is in either a normal or a depressed position, but opened if such button is pulled out from its normal position in which it is biased. The structure of a button to provide such mode of operation can be provided as shown for example, in the application of J. F. Merkel, Ser. No. 158,720, filed August 12, 1937.

Each of the exit buttons **XB** is of the self-restoring type having a contact closed only when such button is depressed from its normal position.

Although separate entrance exit buttons **NB** and **XB** are provided for this embodiment of the present invention, it is desired to be understood that a single button can as well be provided for each of the signal locations for designation of both entrance and exit points at such location, there being circuit or structural means provided for differentiating between the various entrance and exit operations in the designation of the various route ends.

Associated with the establishment of each route through the track layout responsive to the designation of its ends by the actuation of the entrance and exit buttons are relays **NR**, **XR**, **Y**, **N**, **R**, **WZ**, **L**, **LS**, **NCR**, **RCR** and **G** which are provided in a manner and for purposes substantially as set forth for relays designated by similar letter reference characters in the above mentioned patent to A. Langdon, Patent No. 2,148,865, dated February 28, 1939. Each of the relays **NR** is associated with a particular entrance point and is energized responsive to entrance designation, such relay being maintained energized, dependent for restoration upon passage of a train, or upon the pulling out of the entrance button **NB** for that entrance point. Each of the exit relays **XR** is associated with a particular exit point and is energized responsive to exit designation for that point subsequent to the designation of an entrance point, such exit relay being maintained energized, dependent for de-energization upon the deenergization of the entrance relay **NR** for the opposite end of that route. The relays **N** and **R** are provided for selecting the respective normal and reverse positions of the track switch with which they are associated, and such relays are selectively energized in accordance with the preselecting relay **Y** for that track switch, responsive to the picking up of the exit relay **XR** for the exit end of the route to be established.

The polar neutral switch control relay **WZ** is responsive to the energization of an **N** or **R** switch control relay for that track switch, the function of such relay being primarily to provide a means for allowing the reversal of the switch machine which it governs in mid-stroke, and also to provide a means for insuring the complete operation of a track switch once its operation has been initiated.

The neutral relays **CN** and **CR** provided for the respective normal and reverse operation of each of the track switches are responsive to the distinctive energization of the relay **WZ** for that track switch, and such relays are provided with heavy duty contacts for closing and opening the switch operating circuits, having magnetic blow-out means for extinguishing the arc at such contacts. Such relays also provide circuit means for selecting the switch control circuits in a manner to facilitate the provision of features of the pres-

ent invention relative to cross-protection, and the provision of dynamic breaking for the switch machine motor with which such relays are associated.

5 A polar cross-protection relay **P** is provided for each of the track switches, only one of such relays **2P** being illustrated in Fig. 1B. Such polar relay can be constructed as shown, for example, in the patent to W. S. Henry, Patent No. 1,030,811, dated June 25, 1912, there being a button provided thereon for the restoration of the armature of such relay.

10 Associated with the means for cross-protection, is a circuit breaker **CB**, which is tripped whenever any one of the cross-protection relays **P** is operated by a cross occurring in the control circuits of any one of the switch machines included in the track layout.

15 Having thus considered in a general manner the organization of the apparatus for this embodiment of the present invention, it is believed to be expedient to describe the mode of operation and the principles involved with specific reference to various operating conditions.

Operation

20 Inasmuch as the route establishing means used in this embodiment of the present invention is similar to that disclosed in the above mentioned patent to A. Langdon, Patent No. 2,148,865, dated February 28, 1939, reference can be made to that patent for a more complete disclosure of the route establishing system and a better understanding of its application to complex track layouts. However, for the purpose of describing this embodiment of the present invention, sufficient description of the route establishing means will be included to point out its mode of operation in a general manner, and reference will be made to specific examples, showing how the system functions in governing the simple track layout used in connection with this embodiment of the present invention.

25 *Normal conditions.*—The conditions assumed to be normal are those existing when the track layout is unoccupied by trains, there are no routes established or partially established, and the signals are all at stop. An operator is aware of such normal conditions by the indicator lamps (not shown) provided along the track diagram for indication of such conditions. Each of the track switches in the track layout is, under normal conditions, in the position last required for a route including such track switch, and it has been assumed the last route established through the track layout to be a through route on the lower track requiring the track switches **2** and **3** to be operated to their respective normal positions.

30 Under normal conditions the lock relay **2L** is energized dependent upon the route locking, detector locking, approach locking, or time locking provided in accordance with the requirements of practice in a manner well known to those familiar with the art. A lock stick relay **2LS** is maintained energized upon normal conditions dependent upon the lock relay **2L** by a circuit closed from (+), including front contact **10** of relay **2L**, back contact **11** of relay of **2WZ**, and winding of relay **2LS**, to (-). The correspondence relay **2NCR** is normally maintained energized in accordance with the normal position of the track switch **2** by the energization of a circuit closed from (+), including front contact **12** of relay **2WP**, polar contact **13** of relay

2WP in a right hand position, back contact 14 of relay 2R, and winding of relay 2NCR, to (-). The polar neutral switch repeater relay 2WP is energized in accordance with the normal locked position of the switch machine 2SM over control wires 15 and 16 extending from the relay TWP in the control office to the switch machine 2SM at the track layout.

The circuit breaker CB is energized under normal conditions, in accordance with the normal condition of each of the polar cross-protection relays P, by the energization of a circuit closed from (+), including the upper winding of circuit breaker CB, bus wire 17, a normally closed contact of the relay P for each of the switch machines not illustrated in detail, such contacts being connected in the circuit in series, normally closed contact 18 of the cross-protection 2P, wire 19, and lower winding of circuit breaker CB, to (-).

A circuit is also closed but not energized under normal conditions including the control wires for operation of each of the track switches away from its last operated position. Such closed circuit includes the winding of the cross-protection relay P for that track switch. Thus, for example, a circuit is closed including the reverse control wire 2RW for the switch machine 2SM extending from the right hand terminal of the winding of the cross-protection relay 2P including back contact 20 of relay 2CR, magnetic blowout coil 21, center winding b of the overload relay 2OL, control wire 2RW, reverse contact 22 of the circuit controller of switch machine 2SM, armature A of switch machine 2SM, contact 23 of the circuit controller of switch 2SM, field winding F of switch machine 2SM, brake BR of switch machine 2SM, crank contact CM of switch machine 2SM, and common control wire 2CW, to left hand terminal of the winding of the cross-protection relay 2P.

Route establishment.—In accordance with the principles of the route establishing means used in this embodiment of the invention, an operator in setting up a route designates the entrance point thereof by the depression of the entrance button for that point. The entrance relay NR, associated therewith, responds, and is maintained energized as long as the route is to be maintained established. Responsive to the picking up of a relay NR, a preselecting relay Y is picked up for each track switch that can be trailed in a normal position in an available route from the entrance point which has been designated. The selective energization of the Y relays therefore, in a circuit network conveniently called an "initiating network," provides a closed circuit portion which corresponds to each available route extending from the entrance point which has been designated. Such circuit portion feeds energy from a front contact of the entrance relay NR which is energized to each of the exit relays XR that can be included in an available route extending from such entrance point, thus conditioning such exit relay so that it can be energized if that point is designated by the operator as the exit end of the route to be established. After an exit relay XR is picked up, a stick circuit is closed for maintaining such relay energized, dependent for deenergization upon the dropping away of the entrance relay NR for the entrance end of that route.

Responsive to the picking up of each of the exit relays XR, a normal or a reverse switch control relay N or R is picked up for each of the

track switches included in the route extending between the entrance and exit points which have been designated. The position to which each track switch that is trailed in the route extending from the designated entrance point, is to be operated is selected by the route selecting relay Y for that track switch which is conditioned responsive to entrance designation. The position of each track switch included in the route facing the designated entrance point is selected in accordance with its required position by the cascade energization of the switch control relays N and R beginning with the switch control relays provided for the track switch nearest the designated exit point. Such being the case, the circuits for the track switches facing the designated entrance point are predetermined, in accordance with the positions that would be required if a train were to pass from the designated exit point to the designated entrance point.

Responsive to the picking up of a normal or a reverse relay N or R for each of the track switches included in the route, a circuit is closed to cause the energization of the polar neutral switch control relay WZ for that track switch in a manner to be hereinafter considered.

To consider a specific example of how a route is established responsive to entrance and exit designation by an operator, assume that an operator desires to set up a route when such route is available extending from B to C. Responsive to the depression of the button BNB for designation of the entrance point at B, the relay BNR is picked up by the energization of an obvious circuit closed at contact 8 of button BNB in a depressed position. Upon the picking up of relay BNR, a stick circuit is closed for that relay extending from (+), including contact 8 of button BNB closed both in a normal and a depressed position, front contact 9 of relay BNR, winding of relay BNR, and front contact 24 of the track relay 2TR, to (-).

Upon the picking up of relay BNR a circuit is closed to cause the picking up of relay 2Y (because the track switch 2 is trailed in a normal position from the entrance point at B) extending from (+), including front contact 25 of relay BNR, back contact 26 of relay BXR, back contact 27 of relay 2R, and winding of relay 2Y to (-). Upon the picking up of relay 2Y a circuit is closed extending to the winding of relay CXR to condition that relay for energization so that, upon the depression of button CXB, such relay is picked up by the energization of a circuit extending from (+), including front contact 25 of relay BNR, back contact 26 of relay BXR, back contact 27 of relay 2R, front contact 28 of relay 2Y, wire 29, winding of relay CXR, back contact 30 of relay CNR, and contact 31 of button CXB closed in a depressed position, to (-). The picking up of relay CXR closes a stick circuit at front contact 32 to shunt contacts 30 and 31 out of the circuit just described.

Responsive to the picking up of relay CXR, a circuit is closed to cause the picking up of relay 2N (selected in accordance with the picked up position of relay Y) extending from (+), including front contact 33 of relay CXR, wire 34, front contact 35 of relay 2Y, upper winding of relay 2N, and back contact 36 of relay 2R, to (-). The picking up of relay 2N causes the positioning of the track switch 2 in a manner to be hereinafter described, and after such track switch has been properly positioned, the signal

B governing entrance to the route extending from B to C is cleared.

If there were other track switches included in the route, as is disclosed, for example, in the above mentioned patent to A. Langdon, Patent No. 2,148,865, the picking up of a switch control relay such as relay 2N would close a front contact of a circuit for the energization of a normal or a reverse switch control relay for the next track switch toward the entrance point, and the picking up of such normal or reverse relay in turn would close a front contact to cause the energization of the switch control relay N or R for the next adjacent track switch in a similar manner, such mode of operation being effective until the position of each of the track switches included in the route being set up is definitely selected by the energization of an N or R relay for such track switch.

Switch operation.—After the position of a track switch is selected by the picking up of a relay N or R for that track switch, the polar neutral relay WZ for such track switch responds and causes the energization of a normal or reverse switch control relay CN or CR, dependent upon the position to which the track switch is to be operated. The picking up of a relay CN or CR closes a respective normal or reverse switch control circuit and applies energy to the switch machine for which such control relays are provided in a manner to cause that switch machine to be operated to the required position, the energization of such control circuit being effective to act upon a winding of the overload relay OL for that track switch to provide overload protection.

To consider a specific example of how a switch machine SM is operated in accordance with the picking up of an N or R relay in the selection of a route, assume that an operator causes the establishment of a route in accordance with principles as heretofore set forth requiring the position of the track switch 2 to be reverse as required in setting up a route extending from A to C. The picking up of relay 2R in the establishment of such route causes the energization of the lower winding of relay 2WZ by a circuit closed from (+), including front contact 37 of relay 2L, front contact 38 of relay 2R, and lower winding of relay 2WZ, to (—). The energization of relay 2WZ in accordance with the closing of that circuit causes its polar contacts to be operated to a left hand position and thus close a circuit for the reverse control relay CR extending from (+), including contact 39 of circuit breaker CB, contact 40 of circuit breaker CB, front contact 41 of relay 2LS, front contact 42 of relay 2TR, front contact 43 of relay 2WZ, polar contact 44 of relay 2WZ in a left hand position, wire 45, back contact 46 of overload relay 2OL, winding of relay 2CR, wire 47, front contact 48 of relay 2LS, contact 49 of circuit breaker CB, and contact 50 of circuit breaker CB, to (—).

When relay 2R is picked up in the establishment of the route, the relay 2NCR is dropped away by the opening of the circuit for that relay at back contact 14, and the dropping away of that relay closes a stick circuit for the relay 2LS to maintain such relay energized until the operation of the switch machine 2SM has been completed, extending from (+), including front contact 10 of relay 2L, back contact 51 of relay 2NCR, back contact 52 of relay 2RCR, front contact 53 of relay 2LS, and winding of relay 2LS, to (—).

Upon the picking up of the reverse switch control relay 2CR, a switch operating circuit is closed for the switch machine 2SM extending from (+), including contact 39 of circuit breaker CB, contact 40 of circuit breaker CB, front contact 41 of relay 2LS, wire 54, front contact 20 of relay 2CR, magnetic blowout winding 21, winding b of overload relay 2OL connected in multiple with the thermal resistor 55, reverse control wire 2RW, contact 22 of the circuit controller of switch machine 2SM, armature A of the motor of switch machine 2SM, contact 23 of the circuit controller of switch machine 2SM, field winding F of switch machine 2SM, brake BR of switch machine 2SM, crank circuit controller CM of switch machine 2SM, common control wire 2CW, wire 47, front contact 48 of relay 2LS, front contact 49 of circuit breaker CB, and contact 50 of circuit breaker CB, to (—).

After the switch machine 2SM has completed its operation to its reverse locked position, the contact blocks of the pole changing circuit controller shift to establish a closed circuit for the dynamic braking of the switch machine motor, such circuit being closed from the right hand terminal of the cross protection relay 2P including back contact 56 of relay 2CN, winding 57 of the magnetic blowout associated with contact 56, winding c of overload relay 2OL in multiple with the thermal resistance 58, normal control wire 2NW, contact bar 22 of switch machine 2SM, armature A of switch machine 2SM, contact 23 of the pole changing circuit controller, field winding F of switch machine 2SM, brake BR of switch machine 2SM, crank contact CM of switch machine 2SM, and common control wire 2CW to the left hand terminal of the cross protection relay 2P. The polarity applied to such circuit is, of course, opposite to the polarity required for the operation of the motor of the switch machine 2SM in the same direction of rotation, so thus the energy applied to the normal control wire 2NW during the period when the dynamic braking is effective is of a negative polarity and therefore provides that energy flows through the winding of the cross protection relay 2P in a direction not effecting its operation. Energy flowing through that circuit at that time maintains the brake BR energized and thus prevents its application until the motor has practically come to a stop.

After the motor of the switch machine 2SM has come to a stop, the brake BR is deenergized and becomes effective to prevent the rotation of the armature A until energy is again applied to a control circuit for the switch machine 2SM. After the track switches are locked in their reverse positions, the relay 2WP is picked up with its polar contacts operated to a left hand position in accordance with the polarity selected by the point detector contact mechanism in the switch machine 2SM. The picking up of relay 2WP closes a circuit for the correspondence relay 2RCR extending from (+), including front contact 12 of relay 2WP, polar contact 13 of relay 2WP in a left hand position, winding of relay 2RCR, and back contact 59 of relay 2N, to (—). Upon the picking up of relay 2RCR, the stick circuit for relay 2LS is opened at back contact 52 to cause such relay to drop away.

The opening of front contacts 41 and 48 of relay 2LS removes energy from the reverse control circuit for the switch machine 2SM and causes the dropping away of relay 2CR. The reverse control circuit for the switch machine 2SM has, however, been opened prior to the dropping

away of relay 2LS by the shifting of contact 22 of the pole changing circuit controller of the switch machine 2SM.

It is provided by a stick circuit for the relay 2WZ that once the operation of the switch machine 2SM has been initiated, an opportunity for the switch machine to complete its operation is provided, irrespective of the restoration of the route establishing means. Thus, to consider the condition just described with reference to the establishment of a route from A to C, a stick circuit is closed as soon as the relay 2WP is dropped away when the switch machine 2SM starts its operation extending from (+), including front contact 37 of relay 2L, back contact 60 of relay 2WP, front contact 61 of relay 2WZ, polar contact 62 of relay 2WZ in a left hand position, and lower winding of relay 2WZ, to (-). It will be seen that restoration designation by an operator to cause the dropping away of relay 2R will not be effective to cause the dropping away of the relay 2WZ until the switch machine 2SM has completed its operation to its reverse position.

It is believed obvious from the detailed description with relation to the operation of the switch machine 2SM from its normal to its reverse position that a similar mode of operation is effective for causing the switch machine 2SM to be operated from its reverse to its normal position as required when a route is established extending from B to C requiring track switch 2 to be operated from a reverse to a normal position. Under such conditions the relay 2N is picked up, and the picking up of that relay causes the relay 2WZ to be energized by a circuit closed from (+), including front contact 37 of relay 2L, front contact 63 of relay 2N, and upper winding of relay 2WZ, to (-). Upon the picking up of relay 2N, the relay 2RCR is dropped away by the opening of back contact 59. When relay 2WZ is picked up with its polar contacts operated to their right hand positions, the relay 2CN is picked up by the energization of a circuit closed from (+), including contact 39 of circuit breaker CB, front contact 40 of circuit breaker CB, front contact 41 of relay 2LS, front contact 42 of relay 2TR, front contact 43 of relay 2WZ, polar contact 64 of relay 2WZ in a right hand position, wire 65, back contact 66 of relay 2OL, winding of relay 2CN, wire 47, front contact 48 of relay 2LS, front contact 49 of circuit breaker CB, and contact 50 of circuit breaker CB, to (-).

When relay 2CN is picked up, energy is applied to the motor of the switch machine 2SM for operation to a normal position by a circuit closed from (+), including contact 39 of circuit breaker CB, front contact 40 of circuit breaker CB, front contact 41 of relay 2LS, wire 54, front contact 56 of relay 2CN, magnetic blow-out winding 57, winding c of relay 2OL connected in multiple with resistance 58, normal control wire 2NW, contact 22 of the pole changing controller of switch machine 2SM, armature A of switch machine 2SM, contact 23 of the pole changing controller of switch machine 2SM, field winding F of switch machine 2SM, brake BR of switch machine 2SM, crank contactor CM of switch machine 2SM, common control wire 2CW, wire 47, front contact 48 of relay 2LS, front contact 49 of circuit breaker CB, and contact 50 of circuit breaker CB, to (-).

After the switch machine has completed its operation to its normal position, the pole changing circuit controller of that switch machine operates contact 22 to a position to open the con-

trol circuit just described, and closes a circuit for the dynamic braking of the switch machine motor extending from the right-hand terminal of the cross protection relay 2P including back contact 20 of relay 2CN, magnetic blowout winding 21, winding b of overload relay 2OL connected in multiple with resistor 55, reverse control wire 2RW, contact 22 of the pole changing controller of switch machine 2SM, armature A of switch machine 2SM, contact 23 of the pole changing circuit controller of switch machine 2SM, field winding F of switch machine 2SM, brake BR of switch machine 2SM, contact CM of switch machine 2SM, and common wire 2CW to the left-hand terminal of the cross protection relay 2P. Such circuit remains closed but is deenergized after the armature A of the motor of switch machine 2SM has ceased to rotate, and thus the brake BR becomes effective for holding the armature A of the switch machine 2SM in its last operated position.

After the switch machine 2SM has been operated to its normal position and the track switch 2 has been locked, the relay 2WP is picked up with its polar contacts operated to a right-hand position, and the picking up of that relay causes the energization of relay 2NCR. When relay 2NCR is picked up, the stick circuit for relay 2LS is opened at back contact 51, and the dropping away of that relay causes the release of relay 2CN by opening the circuit for such relay at front contacts 41 and 48. The opening of those contacts also of course removes energy from the normal control circuit for the switch machine 2SM.

It will be noted with reference to Fig. 1A that the relays 2N and 2R can also be energized upon the actuation of the auxiliary control lever 2SMI to respective normal and reverse position, thus providing an auxiliary control for each of the track switches which is effective, irrespective of the establishment of routes.

Signal controls.—In order to provide that a signal can be cleared for a route only after such route is completely set up, circuit selections are provided for the control of the signals by the correspondence relays NCR and RCR, and the lock-stick relay LS for each of the track switches. Inasmuch as it has been pointed out that a relay LS is dropped away after its track switch has completed its operation to its required position, it will be noted that the signal B, for example, is cleared only after a route is completely set up from B to C dependent upon the energization of relay BG by a circuit closed from (+), including front contact 67 of relay CXR, wire 68, front contact 69 of relay 2TR, back contact 70 of relay 2LS, back contact 71 of relay 2RCR, front contact 72 of relay 2NCR, back contact 73 of relay BXR, front contact 74 of relay BNR, and winding of relay BG, to (-). The picking up of that relay causes the extinguishing of the red lamp and the illumination of the yellow lamp of signal B upon the shifting of contact 75 to cause such signal to display a proceed indication.

It is believed to be obvious from the example just described how each of the signals can be cleared after a route which it governs has been completely set up, the same circuit selections provided by the contacts of the correspondence and lock-stick relays being used for the energization of signal control relays for signals governing both directions of traffic.

Restoration to normal.—The restoration of the parts of the system associated with the establish-

ment of a route to their normal conditions can be effected either upon the manual designation of such restoration by an operator, or automatically upon the passage of a train through the route established.

As a typical example of how manual restoration is effective, assume that a route has been set up as has been described extending from B to C, and the signal B governing entrance to that route has been cleared. The restoration to normal of the parts of the system associated with the route set up can be initiated by the pulling out of the entrance button BNB for the entrance end of such route. The pulling out of that button causes the dropping away of the relay BNR by opening the stick circuit for that relay at contact 8, and the dropping away of relay BNR causes the dropping away of relay BG by opening the circuit for that relay at front contact 14. The dropping away of that relay of course opens front contact 75 to cause the restoration to stop of the signal B.

The dropping away of relay BNR also causes the dropping away of relays 2Y and CXR by opening the circuits for such relays at front contact 25, and the dropping away of relay CXR opens the pick-up circuit which has been described for the switch position selecting relay 2N. Upon the restoration of the signal B to stop, the lock relay 2L can be energized because of the restoration of the route locking, approach or time locking provided, and the picking up of that relay opens a stick circuit which is closed as long as the electric locking is effective for relay 2N extending from (+), including front contact 76 of relay 2N, back contact 77 of relay 2L, center winding of relay 2N, and back contact 36 of relay 2R, to (-). The dropping away of relay 2N completes the restoration to normal of the parts of the system associated with the establishment of the route from B to C, the relay 2WZ having been dropped away as soon as the lock relay 2L was deenergized upon the clearing of the signal B governing entrance to the route. The dropping away of the relay 2WZ at that time would of course cause the restoration of the switch control relay 2CN by opening the circuit for that relay at front contact 43.

If restoration is to be automatic, dependent upon passage of a train, a very similar mode of operation is effective, the entrance of the train into the route extending from B to C being effective to cause the dropping away of relay BNR by opening the stick circuit for that relay at front contact 24. The dropping away of relay BNR causes the restoration to stop of the signal B and the restoration of the other relays as described except that the relay 2L remains dropped away because of the presence of the train in the route. Such relay when dropped away maintains the stick circuit described for relay 2N energized in order that the contacts 78 and 79 will be maintained open to prevent the so-called "preconditioning" of a conflicting route such as the route extending from A to C. The opening of those contacts prevents the energization of either relay CXR or relay AXR responsive to entrance and exit designation, thus providing that entrance and exit designation for the establishment of a route can be effective only when such route is available for use at the time the exit end thereof is designated by an operator. As soon as the train has left the track section 2T, the restoration of the route locking allows the energization of the relay 2L, and the picking up of that relay allows the dropping away of the relay 2N by opening the stick circuit for that relay at back contact 77.

Overload protection.—If an overload occurs in the switch control circuit during the operation of a switch machine other than just a momentary overload, the energization of a b or c winding of the overload relay OL (dependent upon the position to which the switch machine is being operated) causes the picking up of that overload relay, and such relay in picking up closes a stick circuit for maintaining it energized until restoration is effected by an operator. Upon the picking up of the overload relay under such conditions, the circuit for the CN or CR relay energized at that time is opened, and the dropping away of that relay breaks the control circuit for its switch machine SM, such circuit being opened by heavy duty magnetic blowout contacts that are constructed to most effectively open the circuit carrying an abnormally high amount of current.

As an example of such mode of operation, if the track switch is being operated from its normal to its reverse position as described when an overload occurs, the picking up of relay 2OL due to an abnormal amount of current flowing in the switch control circuit closes a stick circuit for the upper winding a of that relay extending from (+), including contact 39 of circuit breaker CB, front contact 40 of circuit breaker CB, front contact 41 of relay 2LS, front contact 42 of relay 2TR, front contact 43 of relay 2WZ, polar contact 44 of relay 2WZ in its left hand position, wire 45, resistance 60, upper winding a of relay 2OL, front contact 66 of relay 2OL, wire 65, polar contact 64 of relay 2WZ in a left hand position, front contact 48 of relay 2LS, front contact 49 of circuit breaker CB, and contact 50 of circuit breaker CB, to (-). The picking up of the overload relay 2OL opens the circuit for the reverse control relay 2CR at back contact 46, and the dropping away of that relay opens the reverse control circuit for the motor of the switch machine 2SM at front contact 20.

An operator is aware of an overload condition in the operation of the track switch by the usual out-of-correspondence indication displayed by an indicator lamp (not shown) on the control panel of the control machine and in view of such condition he will cause the restoration to normal of the parts of the system conditioned for the route requiring the operation of the switch machine 2SM to its reverse position. In restoring those relays to normal, the relay 2WZ is maintained energized by a stick circuit after such restoration because of the deenergized condition of relay 2WP. To cause the operation of the switch machine 2SM back to its normal locked position, the operator causes the energization of the switch position selecting relay 2N which in picking up energizes the upper winding of relay 2WZ with a polarity to oppose the flux set up in that relay by the energization of the lower winding, and thus cause such relay to be dropped away and to operate its polar contacts to a right hand position. The relay 2WZ is only momentarily dropped away however, and the picking up of that relay with its polar contacts operated to a right hand position reverses the flux in the winding of relay 2OL to provide that such relay will be dropped away and break its stick circuit. With relay 2OL in a dropped away position, the relay 2CN can be picked up by the energization of a circuit which has been described, and the picking up of that relay causes energy to be applied to the normal operating control circuit for the switch machine 2SM to operate that switch machine back to its normal position.

75 The shifting of the pole changing contactor

of the switch machine 2SM is effected because of the energization of the winding NP of such pole changer. The energization of winding NP is effected because contact 82 of the circuit controller is in its dotted position at that time.

It is believed to be readily apparent to those familiar with the art that the operator can cause the switch machine to be operated back and forth as required to free the track switch of obstructions or to overcome other difficulties which could have been the cause of the overload originally encountered in the operation of the switch machine from its normal to its reverse position.

It will be noted that the breaking of the switch machine control circuits under conditions where an overload occurs, or where reversal in mid-stroke is effected without such overload, opens the control circuit by heavy duty contacts provided with magnetic blowout means for extinguishing the arc.

Cross protection.—The use of a cross protection relay P in the control office for each of the track switches provides that a cross between the control wires of any two track switches in the field that could cause an unauthorized operation of one of such track switches will be immediately detected as soon as energy is applied for the operation of either of the track switches involved, and the response of the cross protection relay P under such conditions causes the immediate opening of the circuit breaker CB to deenergize the switch machine control circuits.

As an example of how such cross protection is provided, assume that energy is applied to the reverse control wire 3RW for the switch machine 3SM in a manner comparable to that which has been described for the energization of the reverse control wire 2RW of the switch machine 2SM, and assume at that time that a cross exists in the line wires as indicated by the dotted line 81. The positive energization of the control wire 2RW due to such cross at a time when the switch machine 2SM is in its normal position causes energy to flow from the cross including control wire 2RW, winding b of overload relay 2OL connected in multiple with resistor 55, magnetic blowout winding 21, back contact 20 of relay 2CR, winding of cross protection relay 2P, wire 47, front contact 48 of relay 2LS, front contact 49 of circuit breaker CB, and contact 50 of circuit breaker CB, to (—). Thus, a circuit is completed for the energization of the cross protection relay 2P energized with a polarity that will cause its operation to open the circuit for the circuit breaker CB at contact 18, and thus cause the deenergization of the switch control circuits by the opening of the circuit breaker contacts. The opening of the circuit breaker will of course provide an indication for the operator to call his attention to the condition, and upon examining the polar relays the operator can determine which of the switch machines is involved in the cross occurring between the switch machine control circuits. After the defective condition has been remedied, the operator can restore the cross protection relay 2P by the actuation of the restoration button on such relay, and the restoration of that relay will allow the restoration of the circuit breaker CB, such circuit breaker being of the type that can be restored only when its windings can be energized at a time when manual restoration by an operator is effected.

In a similar manner, if positive energy from another switch circuit were applied by a cross to the normal control wire 2NW with the track

switch 2 in its normal position, the cross protection relay 2P would also be tripped because of the flow of energy from (+), including wire 2NW at the point where the cross occurs, resistor 58 connected in multiple with the winding c of the overload relay 2OL, magnetic blowout winding 57 of relay 2CN, back contact 56 of relay 2CN, winding of the cross protection relay 2P, wire 47, front contact 48 of relay 2LS, front contact 49 of circuit breaker CB, and back contact 50 of circuit breaker CB, to (—). It is believed from the typical examples described when the track switch 2 is assumed to be in its normal position, it will be readily apparent that such circuits are also effective for cross protection when the track switch 2 is in its reverse position to prevent its unauthorized operation.

Having thus described in detail as a specific embodiment the control for the track switches of a simple track layout, it is desired to be understood that this form is selected to facilitate in the disclosure of the present invention rather than to limit the forms that the present invention may assume, and it is to be further understood that various adaptations, alterations and modifications may be applied to the specific form shown without in any manner departing from the spirit or scope of the present invention except as limited by the appended claims.

What I claim is:

1. In a switch and signal control system of the character described for the power operation of each track switch of a track layout upon the manual designation at a control office of the entrance and exit ends of each route extending over such track switch; route establishing means at the control office including normal and reverse switch position selecting relays for each of the track switches responsive to the designation of the respective entrance and exit ends of each of the routes for selecting the position of each of the track switches required to set up such route; a polar cross protection relay at the control office for each of the track switches; a circuit breaker at the control office; a power switch machine for each of the track switches; normal and reverse control wires for each of said power switch machines extending from the control office; circuit means dependent upon said circuit breaker including said control wires for causing the power operation of each of said switch machines in accordance with the position selected by said route establishing means, such circuit means being energized at the control office only when that track switch is out of correspondence with the position selected by said switch position selecting relays, and such circuit means when inactive for control purposes being closed but deenergized including said cross protection relay and one of said normal or reverse control wires for that track switch; and circuit means for energizing said circuit breaker only when each of said cross protection relays has been unaffected by energization of a particular polarity applied under abnormal conditions to such switch control wire.

2. In a switch and signal control system of the character described for a track layout having a plurality of conflicting routes provided by a track switch extending between entrance and exit points; a power driven switch machine for said track switch; a miniature track diagram of the track layout at a control office having disposed thereon manually operable control buttons for designation of the respective entrance

and exit points; route establishing means at the control office including normal and reverse switch position selecting relays for said track switch responsive to the actuation of said contact means for the respective entrance and exit ends of each available route for selecting the position of said track switch required for such route, irrespective of the position such track has last assumed; a normal and a reverse switch control relay for the track switch; circuit means responsive to said route establishing means for energizing said normal or said reverse switch control relay in accordance with the normal or reverse position of said track switch selected by said route establishing means, only if said track switch is out of correspondence with the position selected by said route establishing means; a cross protection relay at the control office; a circuit breaker at the control office; normal and reverse control wires extending from the control office to said switch machine; switch operating circuit means responsive to the energization of said normal or said reverse switch control relay including one or the other of said control wires for operating said switch machine to a position corresponding to said normal or reverse switch control relay energized, such circuit means when inactive for control purposes being closed but deenergized including said cross protection relay and one of said normal and reverse control wires for that track switch; and circuit means for energizing said circuit breaker except when said closed circuit means including said cross protection relay is abnormally energized with a particular polarity.

3. In a switch and signal control system of the entrance-exit type for the power operation of a track switch upon the manual designation at a control office of the entrance and exit ends of each route desired to be established extending over such track switch, route establishing means at the control office including normal and reverse switch position selecting relays for said track switch effective upon the designation of the respective entrance and exit ends of each of the routes to select the position of said track switch required for such route, an electric motor driven switch machine for said track switch, a normal and a reverse control wire extending from the control office to the switch machine, switch operating circuit means responsive to the selection of a normal or a reverse position for the track switch by said route establishing means including said normal or said reverse control wire for operating said switch machine to a corresponding position, and circuit means rendered effective when said track switch has been properly positioned in accordance with the position selected by said route establishing means to deenergize one of said control wires at the control office and to close a circuit including the other of said control wires to shunt the motor of said switch machine.

4. In a switch and signal control system of the entrance-exit type for a track layout, providing by a track switch governed from a control office a plurality of conflicting routes extending between entrance and exit points; manually operable contact means at the control office for designation of the respective entrance and exit points; route establishing means at the control office including normal and reverse switch position selecting relays effective to select the required position for said track switch in each route having its respective entrance and

exit points designated by the actuation of said contact means; a normal and a reverse switch control relay at the control office for said track switch; circuit means effective in response to the selection of a normal or a reverse position for said track switch by said route establishing means for energizing the corresponding normal or reverse switch control relay, only if said track switch is out of correspondence with the position selected by said route establishing means; an electric motor driven switch machine for said track switch; a normal and a reverse control wire extending from the control office to said switch machine; switch operating circuit means including said normal and reverse control wires effective to operate said switch machine to a position corresponding with the normal or reverse switch control relay energized; and circuit means rendered effective when said track switch is in correspondence with the position selected by said route establishing means to deenergize one of said control wires at the control office and to close a shunt circuit for the motor of said switch machine including the other of said control wires.

5. In a switch and signal control system of the character described for a track layout providing by a track switch a plurality of conflicting routes extending between entrance and exit points, manually operable contact means at a control office for designation of the respective entrance and exit points, route establishing means at the control office including normal and reverse switch position selecting relays for said track switch effective in response to the designation of the respective entrance and exit points of each of the routes to select the position of said track switch required for such route, a normal and a reverse switch control relay at the control office for said track switch, circuit means responsive to the selection of a position for said track switch by said route establishing means for energizing said normal or said reverse switch control relay in accordance with the normal or the reverse position of said track switch selected by said route establishing means, only if such track switch is out of correspondence with the position selected by said route establishing means, an electric motor driven switch machine for said track switch, a normal and a reverse control wire extending from the control office to said switch machine, a polar cross protection relay at the control office for said track switch, switch operating circuit means including said normal and reverse control wires responsive to the energization of said normal or said reverse switch control relays for operating said switch machine to a corresponding position, and circuit means rendered effective when said track switch has been properly positioned in accordance with the position selected by said route establishing means to deenergize one of said control wires at the control office and to close a circuit including the other of said control wires and said cross protection relay to shunt the motor of said switch machine.

6. In a switch and signal control system of the character described for a track layout providing by a track switch a plurality of conflicting routes extending between entrance and exit points; an electric motor driven switch machine for said track switch; a miniature track diagram of the track layout at a control office having disposed thereon manually operable contact means for designation of the respective entrance and exit

points; route establishing means at the control office including normal and reverse switch position selecting relays for said track switch effective in response to the actuation of said contact means for designation of the respective entrance and exit points of each of the routes for selecting the position of such track switch required for such route; a normal and a reverse switch control relay at the control office for said track switch; circuit means responsive to said route establishing means for energizing said normal or said reverse switch control relay in accordance with the respective normal or reverse position for said track switch selected by said route establishing means, such energization being effective only when said track switch is out of correspondence with the position selected by said route establishing means; a polar cross protection relay at the control office for said track switch; a circuit breaker at the control office; a normal and a reverse control wire extending from the control office to said switch machine; switch operating circuit means including said normal and reverse control wires effective to operate said switch machine to a normal or a reverse position in accordance with the energization of a respective normal or reverse switch control relay; circuit means rendered effective when said track switch is in correspondence with the position selected by said route establishing means to de-energize one of said control wires at the control office and to close a shunt circuit for the motor of said switch machine including the other of said control wires and said cross protection relay; and circuit means for energizing said circuit breaker except when said shunt circuit including said cross protection relay is energized with a polarity opposite to that generated by the free run of said motor after driving energy has been removed.

7. In a switch and signal control system of the character described for the establishment of each route extending through a track layout which provides by at least one power switch a plurality of conflicting routes extending between entrance and exit points; manually operable contact means for designation of each of the entrance and exit points; normal and reverse switch position selecting relays for each of the track switches; a polar neutral switch control relay for each of the track switches; a normal and a reverse switch control relay for each of the track switches, each of such switch control relays having contacts of relatively high current carrying capacity; an electrically operated switch machine for each of the track switches; route establishing means responsive to the designation of each of the exit points, subsequent to the designation of the entrance end of an available route extending to such point, for selectively energizing one of said switch position selecting relays, the relay selected being dependent upon the position of the track switch required, for each track switch included in the route extending between such designated entrance and exit points; circuit means responsive to the energization of a switch position selecting relay for each of the track switches for distinctively energizing said polar neutral relay in accordance with the position selected by said route establishing means for that track switch; circuit means dependent upon the energized condition of said polar neutral relay for each of the track switches for energizing said normal or reverse switch control relay for that track switch, the relay selected being dependent upon the polarity

by which such polar neutral relay is energized; circuit means responsive to the energization of said normal or said reverse switch control relay for each of the track switches for operating said electric switch machine for that track switch to a corresponding position, such circuit means including a contactor in the switch machine effective to break the operating circuit of such switch machine when it has completed its operation; and overload switch control means for each of the track switches effective to cause the release of said normal or said reverse switch control relay for that track switch when said switch machine for that track switch draws an abnormal amount of current in operation, whereby said contactor at each of said switch machines breaks the switch control circuit each time the switch machine has completed its operation, and said normal or reverse switch control relay breaks the circuit for said switch machine when there is an overload.

8. In a switch and signal control system for railroads; a track layout having a track switch governed from a control office; manually operable switch control means at the control office having operating positions for designation of the respective normal and reverse positions of said track switch; normal and reverse switch control relays at the control office for said track; circuit means for energizing said normal or said reverse switch control relay when said manually operable switch control means is actuated to a respective normal or reverse operating position, only if that track switch is out of correspondence with the position thus designated; a polar cross protection relay at the control office; a circuit breaker at the control office; a power switch machine for said track switch; normal and reverse switch control wires extending from the control office to the track switch; switch control circuit means responsive to the energization of said normal or said reverse switch control relay including one or the other of said control wires for operating said switch machine to a corresponding position, such circuit means when inactive providing a closed circuit including one of said line wires and said cross protection relay; and circuit means for energizing said circuit breaker, only when said cross protection relay is unaffected by the energization of said switch control circuit means when such means is inactive for the designated power operation of said track switch.

9. In a switch and signal control system for railroads, a track layout having a track switch governed from a control office, a manually operable switch control lever at the control office having operating positions for designation of the respective normal and reverse positions of said track switch, a polar cross protection relay at the control office, a circuit breaker at the control office, a power switch machine for said track switch, normal and reverse switch control wires extending from the control office to the switch machine, switch control circuit means responsive to the actuation of said switch control lever to a normal or a reverse operating position including one or the other of said control wires for operating said switch machine to a corresponding position, such circuit means providing when inactive for the operation of the switch machine, a closed circuit including one of said line wires and said cross protection relay and providing for the deenergization of the other control wire at the control office, and circuit means for energiz-

ing said circuit breaker only when said cross protection relay is unaffected by the energization of said switch control circuit means when such means is inactive for the power operation of said track switch.

10. In a switch and signal control system of the entrance-exit type for a track layout providing by a power switch governed from a control office a plurality of conflicting routes extending between entrance and exit points, manually operable contact means for designation of the respective entrance and exit points, route establishing means responsive to the actuation of said contact means for designation of the respective entrance and exit points of each of the routes for selecting the position required for said power switch in such route, normal and reverse switch control wires and a common control wire extending from the control office to the switch machine, switch operating circuit means including said control wires effective to cause the power operation of said track switch in accordance with the position selected for such track switch by said route establishing means, a cross protection relay at the control office for said track switch, and circuit means effective when said switch operating means is inactive to cause the power operation of said track switch for connecting said normal and said reverse control wires contemporaneously to said common control wire through the winding of said cross protection relay.

11. In a switch and signal control system of the character described for governing from a control office the establishment of each route ex-

tending through a track layout providing by a power switch a plurality of conflicting routes extending between entrance and exit points; manually operable contact means for designation of the respective entrance and exit points; route establishing means responsive to the actuation of said contact means for designation of the respective entrance and exit points of each of the routes for selecting the position required for said power switch in such route; normal and reverse switch control relays for said power switch; circuit means for selectively energizing said normal and reverse switch control relays in accordance with the position selected by said route establishing means, such circuit means being effective only if said track switch is out of correspondence with its selected position; normal and reverse and common switch control wires extending from the control office to the power switch; a cross protection relay at the control office for said power switch; and switch operating circuit means including said control wires effective in response to the energization of one of said switch control relays for causing the operation of said power switch to a corresponding position, such switch operating circuit means being effective at the control office when said normal and reverse switch control relays are both deenergized to connect said normal and said reverse control wires contemporaneously to said common control wire through the winding of said cross protection relay.

CHARLES L. SWANTON.
